UNITED STATES PATENT OFFICE.

AUGUSTUS BAILEY, OF YONKERS, AND ELIAS M. JOHNSON, OF NEW YORK, ASSIGNORS OF ONE-THIRD TO STEPHEN W. BALDWIN, OF NEW YORK, N. Y.

SECTIONAL WATER-TUBE BOILER.

SPECIFICATION forming part of Letters Patent No. 550,578, dated December 3, 1895.

Application filed May 31, 1893. Serial No. 476,173. (No model.)

To all whom it may concern:

Be it known that we, AUGUSTUS BAILEY, of Yonkers, in the county of Westchester, and ELIAS M. JOHNSON, of the city and county of 5 New York, in the State of New York, have invented certain new and useful Improvements in Sectional Water-Tube Boilers, which invention is fully set forth and illustrated in the following specification and accompanying 10 drawings.

The object of this invention is to provide a boiler of large potential compared to space occupied which shall at the same time have a high degree of evaporative efficiency, coupled with the production of steam not only 15 dry in quality, but superheated to any degree capable of use in the service to which the boiler may be employed. The boiler is designed in particular for comparatively- 20 small powers, such as may be required in boats and yachts of moderate dimensions; but the invention may be extended to larger purposes and powers.

The invention will first be described in detail and then particularly set forth in the 25 claims.

In the accompanying drawings, Figure 1 shows in front elevation a boiler constructed according to our invention with the front casing 30 of the boiler removed. Fig. 2 shows the boiler in side elevation with one side casing removed. Fig. 3 illustrates in plan one of the boiler-tubes detached, showing the radial distribution of pins upon its surface, more 35 particularly hereinafter described. In Figs. 1 and 2 said pins, for the sake of avoiding needless repetition of similar parts, are omitted from all but a single tube in said figures, respectively.

40 In the several figures of the drawings the different parts are indicated by reference-letters, as follows, like parts in each figure being indicated by like letters.

A series of vertical tubes A, of cast-steel or 45 other suitable metal, provided with projecting pins a on their exterior or fire surfaces, are assembled and connected in the following-described manner: Each tube A at its sides, near its top and bottom, is constructed with 50 short pipes b c of different diameters, forming

a male and female jointed opening for union in a series of parallel lines or rows, which rows, as shown in the drawings, are set transversely of the furnace. Said tubes are secured together at top and bottom by a long bolt d, 55 passing transversely through said tubes and said pipes, their joints being made tight by inserting therein washers e, preferably of copper, and setting up on the nuts f on the ends of the bolts d. Between the outside tube A 60 of each row and the nuts f at the lower joints of the tubes an annular end piece g is inserted, forming a socket-joint with each outer tube A, and to each of said end pieces is connected a short section-piece h. The sections 65 h are each united to the other by socket-joints k, provided with washers similar to the washers e between the tubes A, and by a long bolt n, running longitudinally of the furnace, and nuts m, as shown in Fig. 2. These 70 sections h as thus united form a horizontal water-leg on each side of the boiler and longitudinally connect at bottom the several transverse rows of tubes A in one common union. From the tops of each tube A in each 75 row, or from such a number in each row as may be deemed necessary, a pipe B leads through a short socket-joint C, secured by a single bolt D to a pipe E, which pipe is connected, as shown in Fig. 1, to the steam-drum 80 F, situated within the smoke-pipe G. The pipe E, or an extension of it, passes into said drum upward, terminating in a downward bend H. From near the base of the steam-drum F downcast pipes K lead downward 85 through short socket-joints M, secured each by a single bolt N to the annular sections g, through which said downcasts communicate with the water-legs h, into which legs the feed-water may be introduced through any 90 approved heaters or furnace-coils, such as are in common use. Near the top of the steam-drum F is placed the steam-pipe P, which may lead in any one of the several directions indicated in the drawings, as preferred. 95

The whole boiler is suitably inclosed within a light sheet-metal casing T, lined with any approved non-conducting material V—such as fire-brick, asbestos, or other equivalent 100

material—a suitable furnace-doorway X and ash-pit Y, with suitable doors therefor, (not shown,) of any approved construction, being provided.

5 The enforced course of the circulation of this boiler is as follows: When steam is forming in the boiler, the steam and water entrained therewith, if any, pass up from the tubes A into and through the pipe E, whence 10 the steam escapes from the water, which falls to the bottom of the drum, leaving dry steam above it. The water then escapes from the drum, through the downcasts K, to the water-legs h, whence the same round of circulation 15 continues upward and downward.

The water-level in the tubes A may be varied greatly, not only with perfect safety from injury to or rupture of the tubes at a low-water level, but without making the steam 20 too moist at a high-water level. With well-proportioned areas of grate and tube heating surfaces the degree of superheating desired in any given case can be quite readily maintained, with varying rates of combustion, by 25 simply varying the height of the water-level in the tubes A. If preferred, the pins a may be omitted from the tubes A, but their presence occupies practically no additional space and materially adds to the efficient heat-absorbing surface of this type of boiler, in which 30 practically the whole heating and steam-generating surface is tube-surface.

While it is preferable to connect the tubes A by means of both lines of socket-joints, yet 35 the upper lines of said joints and their bolts may be omitted without departing from this invention.

In taking this boiler apart or in separately removing any one line or nest of tubes for re- 40 pair or renewal no screw-joints are required to be unscrewed or broken. In order to remove any line or nest of tubes, it is only necessary to remove the top-casing of the boiler and then the leg-bolts n and the short socket- 45 bolts D and N from the pipes connecting the particular line of tubes with the steam-drum. Any nest of tubes when thus disconnected can then be lifted clear of its other assembled elements and removed for replacement or re- 50 pair.

We do not confine ourselves to the particular arrangements of furnace and tubes indicated in the drawings, as the furnace, instead of being located below the tubes, may be located 55 in front of the tubes or below a portion of the tubes and in front of a portion of the tubes, as such arrangements of furnaces and tubes are not uncommon in the construction of boilers.

60 These boilers, though particularly adapted for generating comparatively-small powers, may be largely varied in size, if desired, and any desired number may be conveniently assembled to work "in battery."

65 Having thus fully described our said invention, we claim—

1. In a water-tube-boiler, the combination

of the following named parts: lines of vertical tubes set transversely of the furnace, each tube in each line secured to a fellow-tube by 70 a socket-joint formed thereon and by a bolt passing transversely through said tubes and through the interior of said joints from end to end of each line of tubes; water-legs for said tubes set longitudinally of the furnace; a 75 steam drum; and downcast pipes connecting said drum and water-legs; whereby communication is established for the circulation of water and steam between the interiors of said tubes, said drum and water-legs; substantially 80 as set forth.

2. In a water-tube-boiler, the combination of the following named parts: lines of vertical tubes set transversely of the furnace and provided on their external surfaces with projecting pins, each tube in each line secured to a fellow-tube by a socket-joint formed thereon and by a bolt passing transversely through said tubes and through the interior of said joints from end to end of each line of tubes; 85 water-legs for said tubes set longitudinally of the furnace; a steam-drum; and downcast pipes connecting said drum and water-legs. 90

3. In a water-tube-boiler, the combination of the following named parts: lines of vertical tubes of cast-metal, each of said tubes having cast therewith, on opposite sides thereof, short pipes of different diameters, each pipe of smaller diameter entering the corresponding pipe of larger diameter of a fellow-tube and forming male and female joints; a bolt passing through the interior of said joints from end to end of each line of tubes; water-legs for said tubes; a steam-drum; and downcast-pipes connecting said drum and water-legs; whereby communication is established 100 for the circulation of water and steam between the interiors of the tubes and said drum and water-legs, substantially as set forth. 105

4. A water-tube-boiler provided with vertical tubes united by socket-joints and through-bolts, and connected to a series of short sections bolted together, through socket-joints, and forming a horizontal water-leg, on each side of the boiler, below the socket-joints 115 uniting the lower ends of said tubes; whereby communication is established for the circulation of water and steam between the interiors of the tubes and the water-legs, substantially as set forth. 120

5. A water-tube-boiler composed of vertical tubes united transversely near top and bottom by socket-joints and through-bolts and at bottom by water-legs and through-bolts, and provided, with pipes in communication with said water-legs and a steam-drum; and having downcast pipes in communication with said drum and water-legs; substantially as set forth. 125

6. A water-tube-boiler composed of vertical tubes united transversely near top and bottom by socket-joints and through-bolts and at bottom by water-legs and through-bolts, and provided, at their tops, with pipes in 130

communication with a steam-drum, through socket-joints secured by through-bolts; and having downcast pipes in communication with said drum and water-legs; substantially 5 as set forth.

7. A water-tube-boiler composed of vertical tubes united transversely near top and bottom by socket-joints and through-bolts and at bottom by water-legs and through- 10 bolts, and provided, at their tops, with pipes in communication with a steam-drum; and having downcast-pipes in communication with said drum and water-legs, through socket-joints secured by through-bolts, substantially 15 as set forth.

8. A water-tube-boiler consisting of the fol-

lowing named parts in combination: vertical tubes provided at or near their bottoms with socket-joints; annular end-pieces, as *g*; bolts passing through said socket-joints and end-pieces; short sections, as *h*, connected to said end-pieces and forming water-legs and provided with socket-joints; bolts passing through said sections; a steam-drum; pipes leading from said tubes to said drum; and 20 downcast pipes leading from said drum, through said end-pieces, to said water-legs.
